UNITED STATES PATENT OFFICE.

LINUS H. SHAW, OF BROCKTON, MASSACHUSETTS, ASSIGNOR TO ACME HEEL COMPANY, OF BROCKTON, MASSACHUSETTS, A CORPORATION OF MASSACHUSETTS.

HEEL BASE.

Application filed March 7, 1928. Serial No. 259,656.

This invention relates to heel bases, meaning by the term "heel base" that part of a separate and attachable shoe heel which is formed with a concave cup more or less 5 closely conforming to the convex heel seat of a shoe. Such heel bases may be made of one or more complete lifts, whole or pieced, and a rand, separate from the rest of the heel and separately applied to the shoe to provide 10 a level surface on which a heel body or lift of rubber, leather or other material may be applied and secured; or they may be combined with other elements to form a complete heel prior to attachment to a shoe. Hence 15 for the purpose of this specification the definition of "heel base" includes not only a distinct article consisting of a single complete lift, or a few of such lifts, and an attached rand, but also that part of an entire heel 20 which comprises the base part of the heel and is composed of the rand and the next adjacent complete lift or lifts.

The object of the invention is to make 25 available for use in the manufacture of such heel bases gougings and skivings of leather resulting from the manufacture of shoe parts and constituting waste which has no value except the nominal value of raw material for 30 leather-board manufacture. In pursuance 35 of this object I take the gougings which are formed in the course of cutting a cup in the seating face of an all leather heel, and the skivings from leather counter stiffeners, and combine such gougings and skivings into 40 associated lifts and rands forming merchantable heel bases. In doing so I effect important economies in the manufacture of heel bases and convert relatively valueless scrap into valuable merchandise.

45 I will now more particularly describe the characteristics of the invention with reference to the drawings in which,—

Fig. 1 is a perspective view of a heel base constructed in accordance with this invention from a single heel gouging and a rand composed of a plurality of counter skivings;

50 Figs. 2 and 3 are perspective views of the heel gouging and rand separated from one another;

Fig. 4 is a detail cross section on line 4—4 of Fig. 1;

55 Fig. 5 is a fragmentary perspective view of another embodiment of the invention in which the heel base is made of a complete

gouging, parts of other gougings, and counter skivings;

Fig. 6 is a perspective view of a part of the heel base shown in Fig. 5;

Fig. 7 is a perspective view of the same structure shown in Fig. 6, but partially dismembered in order better to explain its construction;

Figs. 8 and 9 are fragmentary cross sections on line 8—8 and 9—9, respectively, of Fig. 6.

Like reference characters designate the same parts wherever they occur in the several views.

It is a common practice in the manufacture 70 of high grade leather heels to form a depression in one face by gouging out this part of the heel, and then building up the edges of the concavity so formed by adding a rand to form the so-called cup of the heel which 75 adapts it to the convex heel seat of a shoe. The pieces removed by this practice are what I refer to as gougings in this specification. They have approximately the same outline and lateral dimensions as the heels from 80 which they are cut, since the gouging operation is so performed as to remove practically all of the face of the heel within its perimeter, and are of varying thickness, tapering from a thin edge at all of perimeter except the 85 breast end and having their greatest thickness in the middle area. Such a gouging is shown at *a* in the drawings. The heels on which this practice is performed are usually all leather heels. The gougings resulting 90 from this practice, even though composed of the best leather, are waste material and have had heretofore only a nominal value, that of the miscellaneous leather scraps produced in shoe factories and fit only to be ground up or 95 shredded and made into leather-board.

I take such gougings, of the dimensions suitable for the sizes of heel bases I am making, and combine them with rands *b*, taking in each case a rand (single or composite) 100 which has a height or thickness at the outer edge equal to the required height of the finished heel base. The rand is laid on the tapered edge zone of the gouging and cemented thereto, or otherwise secured in any 105 suitable manner. Cement is indicated in the drawings by stippling.

Preferably I make the rand of several strips of leather wedge shaped in cross section. In the form of the invention shown in 110

Figs. 1, 2 and 3, three of such strips are used, designated, respectively, b , b' and b^2 . The tapered edges of the gouging require the rand to be made of greater height at the outer edge 5 than those used with lifts of uniform thickness in building heel bases, and this fact enables me to effect a further economy by using a narrow wedge strip b' between two wide strips b and b^2 , and thus to utilize narrower 10 skivings from the counter stiffeners of shoes, which have heretofore been useless for any purpose and have been thrown in with the scrap to be made into leather-board. The wider skivings from counter stiffeners have 15 heretofore been used for making rands, but only those skivings have been suitable for that purpose which are wide enough to cross the locations in which nails are driven to fasten the heel to the shoe, and those which are 20 so narrow as not to be penetrated and held by such nails have not been suitable for making rands. I use as the rand to be combined with a gouging in my new heel base, two strips, b and b^2 , having sufficient width for 25 the purpose as above explained, and an intermediate strip b' which is not wide enough in itself to serve as a rand, but is placed between the wider strips and is so firmly gripped between them, as well as being bonded to them 30 by cement, as to be securely retained in place, when the heel base is made fast to the shoe, by the attaching nails which pass through the wider rand strips. These strips are preferably all assembled together into the composite rand, shown by itself in Fig. 3, before being applied to the lift formed by the heel 35 gouging a , although they may be built up on the gouging.

In the construction above described, the 40 heel gouging lift has approximately the external form and dimensions required of the finished heel base, or may have some excess to be trimmed off. But I am not necessarily restricted to the use of a gouging so long and 45 wide as this, for the rand may be placed so as to extend beyond its edges. In Figs. 5-9, I have shown how gougings smaller than the finished heel base may be effectively used to make a composite lift of required area 50 having substantial thickness at its edges. In making such lifts I take a gouging a and extend it at the sides and back by tapered pieces c , d and e , which are cut from heel gougings of similar character in such manner 55 that segments of the outline of the heel base are cut in the thick portions of the gougings. The pieces c and d which build out the sides of the piece a are so cut that one end coincides with the breast end of the gouging 60 from which it is cut, while the opposite end tapers off to nothing. These pieces are laid so as to overlap the gouging a , with their thick ends coinciding with the breast end of the piece a and their thick convex sides 65 forming to the shape of the finished heel base.

The piece e , by which the back or rear end of the composite lift is extended, is cut so that its outline which conforms to the curvature of the rear end of the heel lies in the thick part of a heel gouging and its opposite edge, and both ends, are tapered to no thickness. The parts of these pieces and the center gouging which overlap one another are thus in effect scarfed, or complementally tapered so that they make no abrupt variations in 75 thickness at the overlaps.

The heel base containing such a composite lift is completed by the addition of rand strips b and b' , which may be of the same character as those shown in Figs. 1, 3 and 4, 80 including the narrow counter skiving of too slight width to serve alone, or with only one other strip of the same width, as a rand.

From one point of view the pieces c , d and e are parts of a rand, since they cooperate 85 with the strips b and b' to form a complete rand and build up the edges of the heel base to the required height essentially the same as the rand strip b^2 , previously described. But in another aspect they are also parts of a lift, 90 since they also build out the gouging a to the required peripheral dimension and cooperate with the latter in forming a complete lift. While the lift so constituted is a constituent part of the complete heel base, and is claimed 95 as such, nevertheless I do not limit my claim to protection for such lift to its use in this combination only, but I claim it also as a pieced lift available for all uses to which such a lift may be put.

It will be apparent from the foregoing explanation that by the present invention I have created a new utility for scraps from two different sources which have heretofore been 100 only waste.

Although I have described the scraps thus utilized as being leather scraps, it is to be understood that I have not intended to limit my invention in respect to material, for I may use the gougings and skivings from heels and 105 counters of any material. That is, the gougings and skivings are made of the same material as the pieces from which they are cut.

The heel base thus described, alone or combined with additional lifts, may be subjected 110 to the compressing operation usual in the manufacture of heels, whereby the material is compacted and made more dense, the cup or concavity bounded by the rand is given the required contour, determined by the form of the die which engages that face of the base in the compressing operation, and the opposite face of the heel base is made flat and level.

What I claim and desire to secure by Letters Patent is:

1. A heel base consisting of a lift made of a heel gouging and a rand formed in part of a skiving, too narrow to serve by itself as a rand, interposed between and gripped by two other rand pieces of sufficient width.

2. A heel base comprising a lift formed of a heel gouging and a rand having sufficient height at its outer edge to compensate for the beveled formation of such lift.

5 3. A composite heel lift consisting of a heel gouging and pieces of other gouggings laid with their thin edges overlapping the thin edges of the first named gouggings at the opposite sides and at the rear thereof and cut on 10 the outline and to the dimensions of a prescribed heel lift.

4. A pieced heel lift consisting of a heel gouging having a relatively thick central part and thin edges, and edge pieces extending said 15 gouging peripherally to a given outline and a greater thickness, said edge pieces being each a fragment of a heel gouging cut through

the thickest part of such gouging on an outline conforming to a segment of the periphery of the given heel lift outline and laid with its 20 part of diminishing thickness overlapping the beveled edge part of the first named gouging.

5. A heel base composed of the lift set forth in claim 4, a rand strip formed of a narrow counter skiving laid upon said extension edge 25 pieces with its thicker edge in substantial peripheral conformity therewith, and a wider rand strip overlying the preceding rand strip in similar peripheral conformity therewith; all of the pieces herein specified being bonded 30 adhesively to one another.

In testimony whereof I have affixed my signature.

LINUS H. SHAW.
